UNITED STATES PATENT OFFICE.

GEORGE W. BEER, OF LA HABRA, AND WILLIAM C. TRACY, OF FULLERTON,
CALIFORNIA.

AUTOMATIC WATER-FEED.

1,188,609.

Specification of Letters Patent. Patented June 27, 1916.

Application filed July 27, 1915. Serial No. 42,180.

To all whom it may concern:

Be it known that we, GEORGE W. BEER and WILLIAM C. TRACY, citizens of the United States, residing, respectively, at La Habra, in the county of Orange and State of California, and at Fullerton, in the county of Orange and State of California, have invented new and useful Improvements in Automatic Water-Feeds, of which the followings is a specification.

10 Our invention relates to an automatic water feed for boilers and in particular to novel and improved means whereby the water feed mechanism is automatically operated when the water within the boiler falls below a predetermined level.

15 It is an object of this invention to devise novel and improved means whereby a mechanism controlling the steam supply to a pump or injector feeding water to the boiler is opened when the water in the boiler falls below a predetermined level and said steam supply is closed when the water in the boiler again reaches said level.

20 Another object of this invention is to provide a float chamber communicating with the boiler and containing a float which controls the steam supply to the pump or injector for feeding the boiler.

25 Another object of our invention is to provide an easily adjustable gear mechanism for transmitting the movement of the float to the valve which controls the boiler feed pump or injector.

30 With these and other objects in view, the invention consists in the construction and arrangements of the parts hereinafter described and pointed out in the appended claims.

35 In the drawings which form a part of this specification: Figure 1 shows a side elevation partly in cross section of the automatic water feed apparatus. Fig. 2 is a vertical section of the adjustable steam valve operating device taken on line 2—2 of Fig.

40 1. Fig. 3 is a cross sectional view of the adjustable steam valve operating device taken on section line 3—3. Fig. 4 is a detail view hereinafter referred to.

45 50 A cylindrical float chamber 10 is connected with the water space of the boiler by pipe 11 leading from the bottom 10' thereof. Another pipe 12 entering the float chamber near the top establishes communication between the steam space of said boiler and the

upper part of the float chamber. Slidably mounted within the float chamber is a float 14 preferably constructed of a hollow metal body and adapted to rise and fall with the level of the water in the float chamber, the latter being in communication with the water in the boiler. Sufficient clearance is left between the float and the walls of the float chamber to allow any water condensed above said float to pass to the water below. 60 Centrally secured to the upper part of the float and passing through a stuffing box 15 mounted on the closure 16 of the float chamber is a rod 17. This rod is pivoted at the upper end to an arm 18 the latter being in 70 turn pivoted at 19 to a movable arm 20, the other end of arm 20 being secured to pivot 21 carried on a lug 22 extending from the periphery of the upper part of the float chamber. Arm 18 is provided with a series 75 of bores 23 to which a vertical rod 24 is adjustably secured at its lower end.

The upper end of rod 24 is detachably secured to a disk engaging lever 25 by means of a sleeve 26, slidably mounted on rod 24. 80 As shown in Fig. 4, sleeve 26 is provided with a set screw 26' for clamping said sleeve in an adjusted position to rod 24. Extending upwardly from said sleeve and on the side opposite to that of set screw 26' is an 85 upstanding lug 42, adapted to receive the disk lever 25. The disk lever 25 is provided with a series of openings 25' adapted to cooperate with a set screw 43 provided in said lug which set screw holds disk lever 25 in 90 an adjusted relation to rod 24. Said lever is forked at the disk engaging end, one fork member extending to and pivoted on a stud or pin 29 carried on bracket 30, which is fastened at the upper end to steam pipe 33, 95 which supplies steam to the boiler feed pump or injector. The other and shorter fork member of lever arm 25 extends over the face of disk 28 for a short distance, and is provided with a set screw 27 having a 100 thumb nut.

The circular disk 28 is rotatably mounted on stud 29, in front of the long fork member of lever 25, and is provided with a series of recesses, circularly arranged adjacent to the periphery of said disk. The size of the disk is such that it will extend between the forked ends of lever 25, thereby enabling the set screw 27 to engage any one of said recesses 31. The disk 28 is provided 110

with a cam slot 32 which extends from near the outer circumference to adjacent to and passing for some distance beyond the center of said disk.

5 A steam pipe 33 supplying steam to a pump or injector employed for feeding water to the boiler is provided with a globe valve 34 of any preferred construction. The valve disk 35 has a stem 36 extending 10 through a stuffing box 37 and has adjustably secured to its threaded outer end a fork 38. Lock nut 36' retains the threaded end of stem 36 in its adjusted position in the interiorly threaded lug 38' extending from 15 the upper part of fork 38. The outer member of the fork passes in front of the disk and is provided with a stud or pin 39 which engages the cam slot 32 in disk 28. The other member on fork 38 is longitudinally 20 slotted and is disposed between the bracket and the disk. The stud 29 on which the disk 28 is mounted passes through slot 40. A water glass 41 connected to the float chamber indicates the water level therein.

25 From the foregoing description the operation of the automatic water feed apparatus will be readily understood. Assuming that the position of the float 14 in the float chamber is at the water level which it 30 is desired to maintain in the boiler, the set screw 27 is loosened and disk 28 is rotated so as to cause the valve 35 to be seated on its seat, thereby closing the steam supply to the boiler feed pump or injector. Set 35 screw 27 is now secured in one of the recesses 31 of disk 28. When the level of the water in the boiler falls, a corresponding fall of the level of water in float chamber 10 will take place, causing float 14 to fall 40 with it, thereby moving rods 18 and 24 and lever 25 downwardly. Downward movement of lever 25 causes rotation of disk 28, and pin 39 riding in cam slot 32 will be moved vertically downward, thereby moving valve stem 36 downwardly and opening valve 35 and admitting steam to the boiler feed pump or injector. A rise of the water level in the boiler will cause a corresponding rise of water in the float chamber and 45 cause float 14 to move upwardly communicating this movement through rods 18 and 24 and lever 25, disk 28 and valve stem 36 to the steam valve, thereby closing the same as will be understood.

50 55 The steam connection 12 leading from the boiler to the upper part of float chamber 10 will counterbalance the pressure in the float chamber and the movement of the float 14 will be solely due to the level of the 60 water therein.

It should be noted that the disk lever 25 can be adjusted vertically and horizontally in relation to rod 24 by means of sleeve 26 on rod 24, while rod 24 can be adjusted in 65 relation to arm 18. The position of pin 39

engaging the cam slot may also be adjusted by loosening set screw 27 and by turning the disk until pin 39 occupies the desired position in the cam slot, and then setting set screw 27 again. The length of stem 30 of the globe valve may be adjusted by means of lock nut 36'. 70

When the pin 39 is positioned in cam slot 32 near the center of the disk, then, due to the curvature of said slot, the vertical movement of the globe valve 35 will be less for the same movement of lever 25, than when pin 39 is positioned in the cam slot nearer the edge of the disk. It is therefore apparent that accurate adjustment of our automatic boiler feed apparatus can be made, both as to the level of the water desired to be maintained in the boiler, and as to the throw of the globe valve admitting steam to the boiler feed pump or injector. 80

85 We do not limit ourselves to the specific construction shown and described as changes within the spirit of our invention will occur to those skilled in the art.

We claim:

1. In an automatic water feed for boilers, the combination of a closed float chamber communicating with the water space of a boiler, a float in said float chamber, a pipe connecting the steam space of the boiler with the space above said float in said float chamber, a pipe supplying steam to an apparatus feeding water to said boiler, a steam controlling valve in said steam pipe, valve operating means actuated by said float, said means comprising a bracket, a rotatable disk mounted thereon, said disk being provided with a cam slot and with a series of recesses circularly arranged near the periphery of said disk, a slot engaging pin connected to said valve, a disk rocking lever being forked at its disk engaging end, one fork member being pivoted to said bracket, a recess engaging set screw carried on the other fork member, and lever operating means adjustably connected with said float. 90 95 100 105 110

2. In an automatic water feed for boilers, the combination of a float chamber communicating with the water space of a boiler, a float in said float chamber, a pipe connecting the steam space of the boiler with the space above said float in said float chamber, a pipe supplying steam to an apparatus feeding water to said boiler, a steam controlling valve in said steam pipe, valve operating means actuated by said float, said means comprising a bracket, a rotatable disk mounted thereon, said disk being provided with a cam slot and with a series of recesses circularly arranged near the periphery of said disk, a slot engaging pin, an adjustable connection between said pin and said valve, a disk rocking lever, said lever being forked at its disk engaging end, one fork member being pivoted to said bracket, a recess engag- 115 120 125 130

ing set screw carried on the other fork member, and lever operating rods adjustably connected with said float.

3. In an automatic water feed for boilers, 5 the combination of a closed float chamber communicating with the water space of a boiler, a float in said float chamber, a pipe connecting the steam space of the boiler with the space above said float in said float chamber, a pipe supplying steam to an apparatus feeding water to said boiler, a steam controlling valve in said steam pipe, valve operating means actuated by said float, said means comprising a rotatable disk provided 10 with a cam slot, a slot engaging pin, an adjustable connection between said pin and said valve, a vertical guide for said connection, a disk rocking lever, a set screw for adjustably connecting the periphery of said 15 disk on to said lever, and lever operating rods adjustably connected with said float.

4. In an automatic water feed for boilers, the combination of a closed float chamber 25 communicating with the water space of a boiler, a float in said float chamber, a pipe connecting the steam space of the boiler with the space above said float in said float chamber, a pipe supplying steam to an apparatus feeding water to said boiler, a steam controlling valve in said steam pipe, valve operating means actuated by said float, said means comprising a rotatable disk provided 30 with a cam slot, a slot engaging pin, an adjustable connection between said pin and said valve, a disk rocking lever, adjustable disk 35 engaging means carried by said lever, and lever operating means adjustably connected with said float.

In testimony whereof we have signed our names to this specification.

GEORGE W. BEER.

WILLIAM C. TRACY.
